UNITED STATES PATENT OFFICE.

DEDERICK GERSTEIN, OF VASSAR, MICHIGAN, ASSIGNOR TO HIMSELF AND EDWARD H. TAYLOR, OF SAME PLACE, JOHN G. TRUMP, HENRY LUEBKERT, MARTIN REICHLE, AND PAUL TRUMP, ALL OF TUSCOLA COUNTY, MICHIGAN.

PENDULUM-POWER.

SPECIFICATION forming part of Letters Patent No. 369,176, dated August 30, 1887.

Application filed July 23, 1886. Serial No. 208,853. (No model.)

To all whom it may concern:

Be it known that I, DEDERICK GERSTEIN, a citizen of the United States, residing at Vassar, in the county of Tuscola and State of Michigan, have invented a new and useful Pendulum-Power for Running Light Machinery, of which the following is a full, clear, and exact description, reference being had to the accompanying drawings, forming part of this specification, to in which—

Figure 1 is a perspective view, and Fig. 2 is a vertical section of the same on the line $x x$ of Fig. 1.

The object of my invention is to utilize the pendulum-power to run light machinery, dragsaws, &c.; and it consists in the combination of devices hereinafter explained and claimed.

To enable others skilled in the art to make and use my invention, I will proceed to describe the exact means by which I have carried it out.

In the drawings, A represents a frame-work for supporting the operative mechanism. Across this frame, and supported in suitable bearings, I place the shaft B, on which is secured the pendulum-rod B', as shown in Fig. 2. To the lower end of this rod is attached the weight C, and at a point below the shaft B I attach the arm D, the outer end of which is pivoted to the bell-crank lever E. It is evident that by pulling down the arm e of the lever, and then releasing it, the pendulum will be caused to oscillate.

To the upper end of the pendulum-rod is pivoted the bar F, which connects this rod to the arm F' on the shaft G, and also the arm H,

carrying on its free end a toothed pawl, h, resting on the ratchet-wheel I, secured to the driving-shaft J, the said shaft carrying on one end a band-wheel, K, and on the opposite end a balance-wheel, L. To the lower end of the arm F' is pivoted the arm M, carrying on its free end a toothed pawl, m, which is held up against the lower side of the ratchet-wheel I by means of the spring N, as shown in Fig. 2.

It is evident from this construction of my improved machine that when the pendulum is put in motion the two pawls will cause the ratchet-wheel to revolve, which in turn will revolve the band-wheel K through the driving-shaft J, and thus furnish power for running any light machinery, and at a very trifling expense. When the pendulum is once started and the machinery set in motion, all that will be required will be to pull on the lever occasionally to keep the machinery in motion.

Having thus described my invention, what I claim as new, and desire to secure by Letters Patent, is—

The pendulum-rod B' on the shaft B, and carrying the weight C, the arm D, and bell-crank-lever E, in combination with the bar F, the arm F' on the shaft G, arms H and M, carrying toothed pawls, the spring N, and the ratchet-wheel I on the driving-shaft, all constructed and arranged to operate substantially as herein described.

DEDERICK GERSTEIN.
